[57] **ABSTRACT**

A phase detection system for at least one digital phase-modulated wave, in which two products of a phase-modulated digital signal and two reference carrier waves each having the same frequency as the phase-modulated digital signal and a phase difference 90° therebetween are at first produced, so that a converted value which is a function of a phase difference between the phase-modulated digital signal and one of the reference carrier waves is found by integrating respectively the two products or by passing the two products in respective low-pass filters. The phase detection of the phase-modulated wave is performed by comparing the converted value with a reference phase. Compensation means may be further provided to compensate phase error in the converted value.

**PHASE DETECTION SYSTEM FOR AT LEAST ONE
DIGITAL PHASE-MODULATED WAVE**

This invention relates to a phase detecting system for at least one digital phase-modulated wave modulated to quantum or discrete phase positions in accordance with information signal or signals to be transmitted.

As the phase detection system, there are a delayed detection system and a synchronous detection system in a broad classification. The delayed detection system is employed for detecting a differential phase modulated wave so that the phase position of a signal element is compared with the phase position of an immediately preceding signal element to detect a phase difference between two successive signal elements. Accordingly, a delay circuit having a delay time equal to the duration of the signal element is necessary in this system. Moreover, it is necessary that the delay time of the delay circuit is correctly maintained over a necessary frequency range. On the other hand, a reference carrier generator is necessary in the synchronous detection system to obtain a reference phase position. In this case, the phase position of the reference carrier is usually regulated by the use of phase-information transmitted from the sending side or by detecting phase-information from the received signal. In this case, transmission of the phase information is necessary by the use of another communication channel so that this is uneconomical and unusual. Moreover, it is very difficult to detect phase-information from the received signal and regulate the reference carrier generator.

An object of this invention is to provide a phase detection system of a digital phase-modulated wave or waves capable of performing phase detection corresponding to the delayed phase detection system or the synchronous detection system by a single circuit without complicated delay circuits and regulation circuits and suitable to reduce to practice by use of digital circuitry and to form time-divisional circuitry for a plurality of phase-modulated waves.

Another object of this invention is to provide a phase detection system of at least one digital phase-modulated wave capable of performing phase detection by digital operation without use of a reference carrier generator having a feed back loop coupled to the digital phase-modulated wave.

In accordance with a first feature of this invention, two products of a phase-modulated digital signal and respective two reference carrier waves each having the same frequency as the phase-modulated digital signal and a phase difference $\pi/2$ therebetween are at first produced, so that a value which is a function of a phase difference between the phase-modulated digital signal and one of the reference carrier waves is found by integrating respectively the two products or by passing the two products in respective low-pass filters, whereby phase detection of the phase-modulated digital signal is performed.

In accordance with a second feature of this invention, the phase of each signal element of the phase-modulated digital signal detected as mentioned above is temporarily stored as a stored phase, and this stored phase is replaced by a phase position of an immediately succeeding signal element similarly detected by the use of a phase difference between successive two signal elements.

In accordance with a third feature of this invention, a phase representative of digital information to be transmitted is subtracted from a phase difference between the stored phase and the phase-modulated digital signal to obtain an error so that this error is employed to compensate the stored phase so as to produce a compensated stored phase of reference.

As results of the above features, the system of this invention has following merits:

1. Since phase information is represented by digital information, phase information can be correctly represented by increasing the number of digits of the digital information.

2. Even if an oscillator is employed for generating reference carriers, it is not necessary that the frequency of the oscillator is regulated. Accordingly, the stability of the oscillation frequency of the oscillator is very high while feed back means is not necessary. These are suitable to low cost of the system.

3. A plurality of phase-modulated digital signals can be phase-detected in a time-divisional manner, so that the system can be formed in a small size and have a low cost.

25 The principle, construction, operation and merits of the system of this invention will be better understood from the following more detailed discussion in conjunction with the accompanying drawings, in which:

FIG. 1 is a wave form for describing an example of a digital phase-modulated wave applied to the system of this invention;

FIGS. 2 and 9 are vector diagrams explanatory of the principle of phase modulation in a phase-modulated wave applied to the system of this invention;

35 FIG. 3 is a block diagram for illustrating an embodiment of this invention;

FIG. 4 is a flow-chart explanatory of the operation of the system shown in FIG. 3;

40 FIG. 5 is a block diagram for illustrating a part of another embodiment of this invention;

FIGS. 6A, 6B, 7 and 8 are block diagrams each for illustrating another embodiment of this invention;

45 FIGS. 10 and 11 are block diagrams each for illustrating an example of a circuit used in the embodiment shown in FIG. 8; and

FIG. 12 shows characteristic curves explanatory of the operation of the example shown in FIG. 11.

The principle of this invention will first be described.

50 In this case, phase detection of an eight-phase differential phase-modulated wave transmitting three bits of information for each signal element is taken as an example. With reference to FIG. 1 showing a wave form of a received signal, if the instantaneous level, phase-position and amplitude of a signal element and the angle frequency of the carrier are assumed respectively as $S_i(t)$, ϕ_i , w_c and A , the instantaneous level of an i -th signal element $S_i(t)$ can be indicated as follows:

$$S_i(t) = A \cos(w_c t + \phi_i) \quad (1)$$

55 In this case, the time t satisfies a condition $0 \leq t < T$ if the duration of the signal element is indicated by "T". Accordingly, the time t is zero at the start of the signal element and the value T at the termination of the signal element.

60 In this system, a reference carrier wave having the same frequency as the received signal is employed to

detect at first a phase difference between the reference carrier wave and the received signal. To obtain this phase difference, a product of the reference carrier wave and the received signal and a product of the received signal and another reference carrier having a phase position different by $\pi/2$ from that of the reference carrier wave are performed. If the angle frequency and phase position of the reference carrier wave are assumed as values w_s and ϕ_s , while the amplitude of the reference carrier wave is "1" without loss of the general meaning, the product of the reference carrier wave and the received wave can be indicated as follows:

$$A \cos(w_c + \phi_i) \cos(w_s t + \phi_s) \\ = A/2 \cdot \cos((w_c + w_s)t + \phi_i + \phi_s)$$

$$+ A/2 \cdot \cos((w_c - w_s)t + (\phi_i + \phi_s)) \quad (2)$$

This product output is passed through a low pass filter so that a second member of the equation (2) is obtained. In this case, since the value w_c is substantially equal to the value w_s , the output is substantially equal to a value $A/2 \cos(\phi_i - \phi_s)$.

The second member of the equation (2) can be also obtained by integrating the product output during a duration τ equal to $n/2$ -multiple of the period of the carrier wave. In other words, the duration τ is equal to a value $2\pi/w_s n$, where n is a positive integer. Namely, the integration of a first member is as follows:

$$\int_0^\tau A/2 \cdot \cos((w_c + w_s)t + \phi_i + \phi_s) dt$$

$$\doteq \int_0^\tau A/2 \cdot \cos(2w_s t + \phi_i + \phi_s) dt = 0$$

Moreover, since a value $(w_c = w_s)t$ is substantially equal to zero in view of a condition $w_c \approx w_s$, an integration of the second member is as follows:

$$\int_0^\tau A/2 \cdot \cos((w_c - w_s)t + (\phi_i - \phi_s)) dt \\ \doteq A\tau/2 \cdot \cos(\phi_i - \phi_s) \quad (3)$$

In a similar manner, a product of the received signal and another reference signal having a phase position different by $\pi/2$ from the reference carrier is as follows:

$$A \cos(w_c t + \phi_i) \cos(w_s t + \phi_s - \pi/2) \\ = A/2 \cdot \cos((w_c + w_s)t + \phi_i + \phi_s - \pi/2) \\ + A/2 \cdot \cos((w_c - w_s)t + (\phi_i - \phi_s) + \pi/2) \quad (4)$$

The second member only of the equation (4) can be also obtained by passing the product output into a low pass filter. In this case, since a value w_c is substantially equal to a value w_s , the output of the low-pass filter is as follows:

$$A/2 \cdot \cos((\phi_i - \phi_s) + \pi/2) = A/2 \sin(\phi_i - \phi_s)$$

On the other hand, if the product output is integrated during a duration τ , an integration of the first member of the equation (4) is as follows:

$$\int_0^\tau A/2 \cdot \cos((w_c + w_s)t + \phi_i + \phi_s - \pi/2) dt \doteq 0$$

Moreover, an integration of the second member of the equation (4) is as follows:

$$5 \quad \int_0^\tau A/2 \cdot \cos((w_c - w_s)t + (\phi_i - \phi_s) + \pi/2) dt \\ \approx A/2 \cdot \cos((\phi_i - \phi_s) + \pi/2) \\ = A/2 \cdot \sin(\phi_i - \phi_s) \quad (5)$$

This is an output of this integration.

10 If the signals indicated in the equations (3) and (5) are assumed as follows:

$$y_i = A\tau/2 \cdot \cos(\phi_i - \phi_s) \quad (6)$$

$$x_i = A\tau/2 \cdot \sin(\phi_i - \phi_s) \quad (7)$$

15 the following relationship is satisfied.

$$x_i/y_i = \tan(\phi_i - \phi_s)$$

Therefore, a phase difference Φ_i between the received signal having a phase position ϕ_i and the reference carrier wave having a phase position can be indicated as

20 follows:

$$\Phi_i = \phi_i - \phi_s = \tan^{-1} x_i/y_i \quad (8)$$

25 This relationship is also obtained in a case of passing into the low-pass filter by the ratio of two outputs.

As mentioned above, the product of the reference carrier wave and the received signal and the product of another reference wave having a phase position different by $\pi/2$ from that of the reference carrier wave

30 are at first obtained, and values x_i and y_i are obtained by integrating the products or passing the products into low-pass filters respectively. The phase difference Φ_i between the received signal and the reference carrier wave is obtained by the use of the ratio x_i/y_i . However,

35 since a function $\tan^{-1}(x_i/y_i)$ is not a univalent function, the value Φ_i is not uniquely determined for a value x_i/y_i . Therefore, if the following relationship is assumed by the use of an absolute value $|x_i/y_i|$ of the value x_i/y_i , the value Φ_i can be indicated as shown in Table 1 in accordance with the positive or negative conditions of the values x_i and y_i .

$$\Phi_{io} = \tan^{-1} |x_i/y_i| \quad (9)$$

TABLE 1

x_i	y_i	Quadrant	Φ_i
+	+	first	$\Phi_i = \Phi_{io}$
-	+	second	$\Phi_i = \pi - \Phi_{io}$
-	-	third	$\Phi_i = \pi + \Phi_{io}$
+	-	fourth	$\Phi_i = 2\pi - \Phi_{io}$

The value Φ_i can be obtained as mentioned above.

55 Accordingly, when a value Φ_{i+1} of $(i+1)$ -th signal element is similarly obtained, transmitted information can be detected by calculating a difference $(\Phi_{i+1} - \Phi_i)$ in a manner similar to the delayed detection system.

60 In FIG. 2 and Table 2, codes and phase-positions of the eight-phase phase modulated wave are shown. By way of example, if a phase difference d between adjacent two signal elements is included in a range $5/8.\pi < d < 7/8.\pi$, transmitted information of three bits is a code "100".

65 In this example, codes are coded in Gray code. However, codes may be coded in other code configurations, such as normal binary codes. In Table 2, phase dif-

ferences between adjacent two signal elements and Gray codes of the eight-phase phase-modulated wave are shown.

TABLE 2

transmitted codes	ideal phase-difference	decision range of phase-differenced	Multiplier m multiplying unit phase
0 0 0	0	$15\pi/8 \leq d < 2\pi$ or $0 \leq d < \pi/8$	0
0 0 1	$\pi/4$	$\pi/8 \leq d < 3\pi/8$	1
1 0 1	$\pi/2$	$3\pi/8 \leq d < 5\pi/8$	2
1 0 0	$3\pi/4$	$5\pi/8 \leq d < 7\pi/8$	3
1 1 0	π	$7\pi/8 \leq d < 9\pi/8$	4
1 1 1	$5\pi/4$	$9\pi/8 \leq d < 11\pi/8$	5
0 1 1	$3\pi/2$	$11\pi/8 \leq d < 13\pi/8$	6
0 1 0	$7\pi/4$	$13\pi/8 \leq d < 15\pi/8$	7

Three bits of information transmissible on each signal element having eight possible phases or phase positions are shown in a left most column. The phase difference d is represented with respect to an immediately preceding signal element as a reference. A multiplier multiplying a unit phase ($\pi/4$ in this case) corresponds to a transmitted code. The multipliers are shown at a right most column while codes corresponding to the multipliers are shown at the left most column.

With reference to FIG. 3, an example of this invention to perform the above-mentioned principle comprises an input terminal 1 for receiving an input phase-modulated signal, reference signal generator 2 for generating the reference carrier wave f_a having a frequency substantially equal to the frequency of the input signal, a phase-shifter 3 having a phase shifting value $\pi/2$, modulation product circuits 4-1 and 4-2 (e.g.; ring-modulator), integrators 5-1 and 5-2 each repeating integration operation every time τ equal to an integer multiple of one half the period of the carrier of the input signal, samplers 6-1 and 6-2 each sampling the output of the integrator 5-1 or 5-2 for each signal element at the termination of the integrating time τ , a converter 7 (e.g.; conversion table) for converting respective absolute values of the samplers 6-1 and 6-2 to the value Φ_{i0} defined in the equation (9), a converter 8 (e.g.; conversion table) for converting respective outputs of the sampler 6-1 and 6-2 and the value Φ_{i0} found at the converter 7 to the value Φ_i in accordance with Table 1, a memory 9 storing respective values Φ_i and Φ_{i+1} of successive two signal elements, a subtracter 10 for obtaining a difference $(\Phi_{i+1} - \Phi_i)$ to codes in accordance with Table 2, and an output terminal 12 for the detected code.

In operation, the input signal is applied from the input terminal 1 to the modulators 4-1 and 4-2, so that a product of the received signal and the reference carrier wave f_a is obtained at the output of the modulators 4-1 while a product of the received signal and another reference carrier wave f_b having a phase position different by $\pi/2$ from the phase position of the reference carrier wave f_a is obtained at the output of the modulator 4-2. These outputs of the modulators 4-1 and 4-2 are respectively defined by the equations (2) and (4) and applied respectively to the integrators 5-1 and 5-2 so as to be integrated for a time substantially equal to an integer multiple of one half the period of the carrier. These integration operations are performed for each

signal element in synchronism with bit timing pulses applied from terminals 5-0. The bit timing pulses are usually transmitted from the sending side but may be independently generated at this receiving side. The values y_i and x_i defined by the equations (3) and (5) respectively are obtained from the integrators 5-1 and 5-2 respectively. These outputs are sampled at the samplers 6-1 and 6-2 respectively and applied to the converters 7 and 8. The value Φ_{i0} is obtained at the converter 7 from a ratio of the absolute value $|x_i|$ to the absolute value $|y_i|$. The value Φ_{i0} and the sampled outputs of the samplers 6-1 and 6-2 are converted to the value Φ_i at the converter 8. The output Φ_i of the converter 8 is stored in the memory 9, and the difference $(\Phi_{i+1} - \Phi_i)$ is obtained from the subtracter 10 and applied to the code 11. At the output terminal 12, a code corresponding to the difference $(\Phi_{i+1} - \Phi_i)$ is obtained.

In the above mentioned principle, a transmitted code 20 is detected by the use of a difference between values $\Phi_{i+1} - \Phi_i$ which are found for successive two signal elements similarly to the delayed detection system. The above mentioned value Φ_i can be applied to perform synchronous detection as follows.

In this synchronous detection system, a phase regulation circuit for synchronizing the phase position of a reference carrier wave with the received signal is not employed. In the above-mentioned detection principle, 30 the phase position Φ_i of an immediately preceding signal element is stored to find the difference between this phase position Φ_i and a phase position Φ_{i+1} of a succeeding signal element. In this detection system now mentioned, however, a code corresponding to a difference $\Phi_{i+1} - \theta_i$ between a phase position Φ_{i+1} and a reference phase position θ_i obtained in accordance with the received result of an immediately preceding signal element is found in accordance with the principle shown in Table 2. If following conditions are 35 satisfied, namely:

$$\Phi_{i+1} - \theta_i = d_{i+1}$$

$$d_{i+1} = m_{i+1} \cdot \pi/4$$

45 where " m_{i+1} " is equal to a value 0, 1, 2, 3, 4, 5, 6 or 7, the value Φ_{i+1} is stored after changing to a value θ_{i+1} . In this case, it is conceivable that the stored phase position is synchronized with the received signal.

50 If a condition:

$$d_{i+1} \neq m_{i+1} \cdot \pi/4$$

is satisfied, a phase difference is shown by a value $(d_{i+1} - m_{i+1} \cdot \pi/4)$.

55 If the value $(d_{i+1} - m_{i+1} \cdot \pi/4)$ is assumed a a value r_{i+1} , a following condition is satisfied.

$$-\pi/8 < r_{i+1} < \pi/8$$

60 In this case, the phase position of signal element is indicated by a value $m_i \cdot \pi/4$ since an eight-phase phase-modulated wave is taken as an example. However, in a case of a N-phase phase-modulated wave, the phase position of signal element is indicated by a value $m_i \cdot \pi/N$ while a condition: $-\pi/N < r_i < \pi/N$ is satisfied. In this principle, a value θ_{i+1} indicated by a following condition:

$$\theta_{i+1} = |\theta_i + m_{i+1} \cdot \pi/4 + K \cdot r_{i-1}|$$

is stored to compensate an error of phase position. In this case, " || " shows a notation of mode 2π , so that if the value of a sum shown within the notation exceeds the value 2π this value 2π is subtracted from the sum to obtain the value θ_{i+1} . A difference $\Phi_{i+1} - \theta_i$ is found for the receiving of each signal element by the use of the phase position Φ_{i+1} of the signal element and a phase position θ_i stored as mentioned above. Moreover, a code corresponding to the signal element is obtained from a multiplier m_{i+1} of a unit phase corresponding to a phase difference d_{i+1} in accordance with the principle shown in Table 2.

The above principle will be further described in details with reference to a flow chart shown in FIG. 4. It is assumed that a transmitted code is detected from an i -th signal element and a compensated phase position θ_i is stored in the memory. When an $(i+1)$ -th signal element is received, the phase position thereof is found as mentioned above. In this case, a difference $\Phi_{i+1} - \theta_i$ is at first calculated as shown in the flow chart of FIG. 4. If the difference $\Phi_{i+1} - \theta_i$ is less than zero, a sum $\Phi_{i+1} + 2\pi - \theta_i$ is found and applied to a register R. However, if the difference $\Phi_{i+1} - \theta_i$ is stored in the register R. If the contents r of the register R do not satisfy a condition: $-\pi/8 < r < \pi/8$, a difference $r - \pi/4$ is found and "1" is added to a counter. Thereafter, the condition: $-\pi/8 < r < \pi/8$ is again tested. If the condition: $-\pi/8 < r < \pi/8$ is satisfied, the contents m_{i+1} of the counter at this instant are coded to a code in accordance with the principle shown in Table 2 so that the code is sent out to the output. Moreover, a sum $|\theta_i + \pi/4 \cdot m_{i+1} + K \cdot r_{i+1}|$ is found from the contents r_{i+1} of the register at this instant and stored, as a stored phase θ_{i+1} , in the memory. In this case, a value K is a coefficient which meets with a condition: $0 < K < 1$.

In the above explanation, it is assumed that a stored phase is already stored. However, it is not known what value is stored in the memory when a first signal element is received. The stored value is compensated for receiving of each signal element by repeating the above-mentioned operations, so that the stored value is corrected to a correct value. The speed of this correction is determined in accordance with the value of the coefficient K. If the coefficient K is equal to "1" as an extreme case, this phase detection corresponds to the delayed phase direction in which phase detection of a signal element is performed with respect to the phase position of an immediately preceding signal element as a reference. On the other hand, if the coefficient K is equal to zero, a value θ given at first is completely synchronized with the received signal so that this synchronized condition is thereafter maintained.

With reference to FIG. 5, an example of a circuit performing the above-mentioned synchronous phase detection will be described. In this example, a memory 9 is the same as the memory 9 shown in FIG. 3 and stores the phase position of a received signal element. A memory 14 stores the above mentioned stored phase θ_i . A calculating circuit 13 (e.g., conversion table) produces a difference $\Phi_{i+1} - \theta_i$ by the use of the value Φ_{i+1} applied from the memory 9 and the stored phase θ_i applied from the memory 14. If a condition: $\Phi_{i+1} - \theta_i < 0$ is not satisfied, the difference $\Phi_{i+1} - \theta_i$ is stored in a register 15. However, if a condition: $\Phi_{i+1} - \theta_i < 0$

satisfied, a value $\Phi_{i+1} + 2\pi - \theta_i$ is stored in the register 15. A calculating circuit 24 tests whether or not the contents r of the register 15 meet with a condition: $-\pi/8 < r < \pi/8$ in a case of detection of a eight-phase phase-modulated wave. If the contents r are not included within the above range, the contents r are applied through a gate circuit 16 to a calculating circuit 21. This calculating circuit 21 produces a difference $r - \pi/4$ which is again stored in the register 15 through a delay circuit 19 having a very small delay time.

Moreover, the pulse from the calculating circuit 24 is applied to a counter 22. The contents r newly stored in the register 15 are tested by the calculating circuit 24. The above-mentioned condition: $-\pi/8 < r < \pi/8$ is not satisfied, the above mentioned operations are repeated. When the condition: $-\pi/8 < r < \pi/8$ is satisfied, the contents r of the register 15 passes through a gate circuit 17 opened in response to the pulse from the calculating circuit 24 and is applied to a calculating circuit 25. On the other hand, the contents m_i of the counter 22 are converted to a code in a converter 23 in accordance with the principle shown in Table 2 to send out the code to an output terminal 26 through a gate circuit 18. The counting state of the counter 22 is reset at once in response to the output pulse of the calculating circuit 24 applied through a delay circuit 20. The calculating circuit 25 produces a sum $\pi/2 \cdot m_i + K \cdot r$ by the use of the contents r of the register 15 and the contents m_i of the counter 22 so as to be stored in the memory 14 and a new stored phase θ_i .

An example of obtaining the timing pulses for controlling the integration period of the integrators (5-1, 5-2) will now be described. In a case where a modulation product of the received signal and the output of the reference carrier wave is performed at the modulator (4-1, 4-2) as mentioned above, the output of the modulator can be divided into two parts one of which has a frequency substantially equal to the frequency of the reference carrier wave and the other of which is a low-frequency signal having an instantaneous level changed in accordance with only digital information transmitted. If this low-frequency signal is separated from the former component by a low-pass filter, the timing pulses can be obtained so as to synchronize with characteristic instants of the low-frequency signal since the level of the low-frequency signal varies in accordance with digital information transmitted. Moreover, since the output of the low-pass filter (i.e., the low-frequency signal) is proportional to values x_i and y_i , this output of the low-pass filter can be used in the place of the values x_i and y_i .

A separated channel may be employed to transmit bit timing information for integration and sampling. Moreover, it is desirable that the integrating time for integrating the output of the modulator (4-1, 4-2) for each signal element is substantially equal to an integer multiple of one half the period of the carrier as mentioned above. However, if the period of the carrier is sufficiently smaller (e.g., less than one several-th) than the duration of the signal element, integration error will be small even if the integration time is determined irrespective of the period of the carrier. Accordingly, the integration time may be determined so as to be equal to or smaller than the duration of the signal element irrespective of the period of the carrier. Furthermore,

the values of phase are represented in radians. However, values of phase represented in degrees can be also handled in this system.

In the above explanation, it is assumed that a phase-modulated wave is applied to the system of this invention. However, if a plurality of phase-modulated waves are applied to this system, common circuitry provided after the samplers (6-1, 6-2) can be used time-divisionally for the phase-modulated waves. Moreover, if the input signal is at first sampled and coded to a binary signal, all the circuits can be formed by digital circuits. If a high speed calculating circuit can be employed, the above mentioned modulation product and integration can be performed by a common calculating circuit.

With reference to FIG. 6A, an example, of this invention for receiving a plurality of phase-modulated waves having the same frequency comprises a reference carrier generator II which is the same as the reference carrier generator 2, a phase shifter III which is the same as the phase shifter 3, a scanning sampler I for scanning input signals applied from input terminals $I_1, I_2, \dots, I_n$, reference carriers obtained from the reference carrier generator II and the phase shifter III by the use of sampling pulses applied from a control circuit VII, a coder IV for coding the sampled output of the scanning sampler I, a memory V for temporarily storing the coded output of the coder IV, a calculating circuit VI for performing the above mentioned calculation for the contents of the memory V, and the control circuit VII for applying timing information to the circuits I, IV, V and VI.

If a read-only memory VIII is provided for semipermanently storing respective sampled values of the reference carriers after coded as shown in FIG. 6B, the reference carrier generator II and the phase shifter III can be eliminated. In this case, contents of the read-only memory VII is repeatedly read-out without sampling and coded for each sampling period as shown in FIG. 6A. Moreover, since two reference carriers have only a phase difference between each other, a common memory table can be used in a normal address condition and a condition where addresses are shifted from the normal address condition. In this case, however, a clock is necessarily provided in the control circuit VII so as to synchronize with the cycle of the reference carrier wave.

The above-mentioned explanation relates to detection operation of an eight-phase phase-modulated wave. However, the system of this invention can be applied to detect at least one phase-modulated wave having 2^n possible quantum phase positions for transmitting n bit or bits of digital information on each signal element.

In the above explanation, it is assumed that the modulation product circuit (4-1, 4-2) produces an output signal having positive and negative possible polarities. However, if the modulation product circuit (4-1, 4-2) produces an output signal of single polarity, two circuits are necessary for the modulation product circuit (4-1 or 4-2).

With reference to FIG. 7, an example of this system for commonly phase-detecting a plurality of phase-modulated waves is provided with a plurality of reference carrier generators II-1, II-2, ..., II-n for generating reference carrier waves respectively having

the same frequency as frequencies $f_1, f_2, \dots, f_n$ of the phase-modulated waves, and a plurality of phase shifters III-1, III-2, ..., III-n.

With reference to FIG. 8, another example of this invention will now be described. This example comprises, an input terminal A, a PGM coder B, a code converter C, a reference carrier generator D, an accumulator E, a code converter F, a code converter G for detecting transmitted phase information, and an output terminal H.

It is assumed that a plurality of eight-phase differential phase-modulated waves bit-synchronized with each other and allocated in frequency spaces 1/T Herz are applied to the input terminal A. In this case, the time T is equal to or slightly less than the duration of each signal element of the phase-modulated wave. Eight quantum phases and codes to be transmitted on one of the eight-phase differential phase-modulated waves are shown in FIG. 9. Vectors shown in FIG. 2 indicate phase-shift from a reference phase (i.e.; phase position of vector MMM) in response to combination of mark (M) and space (S) of three channels or bits I, II and III. The above mentioned eight-phase differential phase-modulated waves are applied to the PCM coder B, which samples the applied signal by sampling pulses of several tens kilo-Hertz and codes PCM codes of 10 bits by way of example. These PCM codes are code-converted at the code converter C by the use of two reference carrier waves having a phase difference $\pi/2$ therebetween supplied from the reference carrier generator D. This code conversion corresponds to phase detection in an analogue system. The outputs of the code converter C obtained for the two reference carrier waves respectively are applied to the accumulator E, which accumulates separately the two outputs of the code converter C during each signal element and ends out respective accumulated results at the termination of each signal element to the code converter F. This operation corresponds to integration operation of an analogue system. If it is assumed that respective phase differences between one of the reference carrier waves and the input signal and between the other of the reference carrier waves and the input signal are values Φ_i and $\Phi_i - 90^\circ$ respectively, the two output codes of the accumulator E correspond respectively voltages proportional to $\cos \Phi_i$ and $\sin \Phi_i$ respectively. Accordingly, the two output codes of the accumulator E can be converted to a code representative of the value Φ_i in the code converter F as mentioned below. The output of the code converter F is applied to the code converter G, which detects transmitted digital information in view of the principle of differential phase-modulation as mentioned below.

Respective parts of the example shown in FIG. 1 will be further described in details below. The PCM coder can adopt any type of PCM code. However, it is assumed in this case that the output code of the PCM coder B is "a folded binary code". Moreover, it is assumed that the folded binary code is derived therefrom as a parallel configuration. However, if successive logical circuitry is designed so as to perform high speed operation, the output code of the PCM coder B may be derived therefrom in serial configuration.

The reference carrier generator D generates, for each phase-modulated wave, two reference carrier

waves of rectangular wave form which have the same frequency substantially equal to the frequency of the phase-modulated wave and a phase-difference 90° from each other.

The code converter C converts the output of the PCM coder B in response to respective polarities "1" and "0" of the two reference carrier waves from the reference carrier generator D. In this case, it is assumed for simple explanation that the number of the phase-modulated wave is one and the number of the reference carrier wave is also one. The most significant digit (MSD) of the PCM code is compared with the polarity of the reference carrier wave, so that the MSD is modified to "1" and "0" in response to the same polarity and different polarities of the above compared digit and wave. The PCM codes in which only the MSD is modified as mentioned above are applied to the accumulator E.

The accumulator E accumulates the converted PCM codes during the duration of each signal element and sends out the accumulated results at the termination of each signal element.

As mentioned above, respective phase detection between one of the two reference carrier waves and the input phase-modulated wave and between the other of the two reference carrier waves and the input phase-modulated wave as well as integration of the respective results of the phase detections are digitally performed. The above phase detections are time-divisionally performed for the two reference waves by supplying alternately the two reference carrier waves from the reference carrier generator D to the code converter C. Moreover, two stages of registers are provided at the accumulator E to as to be connected in cascade with the accumulator E while the output of the two stages of registers are fed back to the accumulator E, so that contents of a preceding one of the two stages of registers are shifted to a successive one of the two stages of the registers in synchronism with the switching of the two reference carrier waves.

To handle a plurality of phase-modulated waves, a plurality of pairs of reference carrier waves are generated from the reference carrier generator D, and a plurality of combinations (two stages) of registers are provided in the accumulator E similarly as mentioned above, so that the registers are switched in synchronism with the switching of the carrier waves.

If two signals applied from the accumulator E to the code converter F are assumed as "x" and "y", these signals "x" and "y" can be indicated as $A \sin \Phi_i$ and $A \cos \Phi_i$. This code converter F converts the values $A \sin \Phi_i$ and $A \cos \Phi_i$ to a value Φ_i indicated as a coded digital signal. In this case, this conversion may be performed by the use of a conversion table of $\tan^{-1} z/y$ after obtaining a quotient x/y . However, division is unsuitable to high speed logical operation. Moreover, since the conversion table is designed for all combinations of values x and y , the device will become a very large size in accordance with the increase of the number of bits of the values x and y .

To eliminate the above defect, inhibited combinations of values x and y may be removed from the conversion table. In this case, since the required value Φ_i is equal to a value $\tan^{-1} x/y$, the value Φ_i is not varied even if the respective values x and y are multiplied by the same multiplier. Accordingly, if respective MSD of the values x and y are both "0", the values x and y are both

multiplied by a multiplier 2^N (where "N" is an integer) to shift by N bits so that the MSD of either the value x or y becomes always "1". Thereafter, combinations in each of which MSD of both the values x and y assume "0" are eliminated to increase preciseness. In Table 3, examples of inhibited combinations in a case where values x and y are each indicated by three bits of binary information are shown by mark (*)

An example of the code converter F to perform the above-mentioned operation shown in FIG. 10 comprises a shift register 21 shifting signals x and y applied from terminals 20-1 and 20-2 respectively, a conversion table 22 formed by a semipermanent memory by way of example, and a modifier 23 modifying the output of the conversion table 22 by the use of the shifted information from the shift register 21.

As mentioned above, the output of the code converter F for one of the phase-modulated waves becomes codes each indicative of a phase difference between the input phase-modulated wave and either one of the two reference carrier waves. If it is assumed that each of the output codes of the code converter F is formed by eight bits of binary information, one complete phase cycle 360° can be represented by 256 steps. Accordingly, each of the quantum phase positions is precisely indicated by the use of a minimum value $360^\circ/256$ ($\approx 14^\circ$). In a case where the input phase-modulated wave has eight quantum phase positions, the contents of the eight bits of binary information vary for each signal element by a value equal to an integer multiple of a unit quantum phase 45° except the combination of polarities MMM of three channels as shown in FIG. 9. Moreover, a phase difference between adjacent two signal elements effectively varies in accordance with a frequency difference between the input phase-modulated wave and the two reference carrier waves. Accordingly, this phase difference Φ_i can be indicated as follows in a case of eight quantum phases.

$$\Phi_i = K \cdot \pi/4 + \theta_i = (K + n) \cdot \pi/4 + (\theta_i - n \cdot \pi/4)$$

where

K: an integer 0, 1, 2, 3, 4, 5, 6 or 7 determined in accordance with the principle shown in FIG. 9;

θ_i : a phase difference between the phase-modulated wave and the two reference carrier waves; and

n: an integer determined so as to make a value $(\theta_i - n \cdot \pi/4)$ less than the unit phase $\pi/4$. Accordingly, the phase difference θ_i can be indicated by the use of a value less than the unit phase $\pi/4$. Since an angle less than the unit phase $\pi/4$ can be indicated by lower value five bits in a pure binary code, the drift of the phase can be detected from the lower value five bits while a shift value between any two of the eight quantum phase positions and equal to an integer multiple of the unit phase $\pi/4$ can be indicated by the upper value three bits.

With reference to FIG. 11, an example of the code converter G will be described. In FIG. 11, a signal e_4^8 shows that this signal e consists of five digits from a fourth digit to an eight digit by way of example. The input of this code converter G applied from the code converter F is shown as a signal a_1^8 and applied to a cascade arrangement of a subtracter S_1 , a code converter C_1 and an accumulator I_1 . This cascade arrangement is smoothing means for compensating the above-mentioned phase fluctuation less than the unit phase $\pi/4$. The accumulator I_1 performs an integration operation as mentioned above, and digits b_4^8 from output digits b_1^{11} of this accumulator I_1 are fed back to the subtracter S_1 , in which the digits b_4^8 are subtracted from the digits a_1^8 . Digits b_1^3 and digits b_9^{11} are neglected without feedback to the subtracter S_1 . However, the digits b_1^3 are shifted by three digits to higher digits so that the feed back value is multiplied by one-eighth. As the subtraction of the digits b_4^8 from the digits a_1^8 at the subtracter S_1 , an error c_1^5 from a desired value of compensation is obtained from the subtracter S_1 as a positive value since the digits a_1^8 show only positive values. However, if negative digits are desirable to raise the convergent speed of the compensated output b_1^{11} , the digits c_1^5 are converted to negative digits at the code converter C_1 . If it is assumed that the digits c_1^5 are indicated by a pure binary code and the error shown by the digits c_1^5 increases, the digits c_1^5 vary from a state "0 0 0 0 0" to a state "1 1 1 1 1" and then restores to the state "0 0 0 0 0". In this case, the convergent speed of the output digits b_1^{11} becomes higher in a case where a range from a state "0 0 0 0 0" to a state "0 1 1 1 1" is positive while a range from a state "1 0 0 0 0" to a state "1 1 1 1" is negative. Accordingly, if the digits c_1^5 are included in the range from the state "0 0 0 0 0" to the state "0 1 1 1 1", the digits c_1^5 are applied to the accumulator I_1 without code-conversion in the code-conversion in the code converter C_1 . In this case, the accumulator I_1 successively adds the error signals (c_1^5) until convergence. However, if the digits c_1^5 exceed the state "1 0 0 0 0", the digits c_1^5 are converted to a code which corresponds to a sum of the digits c_1^5 and a number "2016" indicated by a decimal representation. In other words, while the digits c_1^5 more than the states "1 0 0 0 0" correspond to numbers sixteen to thirty-one indicated by a decimal representation, the digits c_1^5 are converted to any of numbers minus 16 to minus 1. To perform this operation, since the accumulator I_1 is designed so as to have eleven bits of code configuration, complements for the full range (i.e.; 2048 of

decimal representation) of the 11 bits of information are produced in the code converter C_1 if the error is negative. The 11 bits of code configuration at the accumulator I_1 consists of eight bits covering 2π radians and three bits for shifting by three bits as feed back. Accordingly, if the error is a number "31", this error is converted at the code converter C_1 to a number $31 + 2016 = 2047$. In this case, "1" is subtracted from the contents of the accumulator I_1 . As mentioned above, the contents of the accumulator I_1 is accumulated in the positive direction until a value + 15 of the error and in the negative direction until a value - 16 of the error. Accordingly, phase error included in the output of the code converter F is effectively compensated in the compensation means comprising the circuits S_1 , C_1 and I_1 .

Since the reference carrier generator D is provided independently against the input phase-modulated wave, the reference carrier wave and the input phase-modulated wave have usually a frequency difference df . In this case, the above mentioned phase difference Φ_i drifts in a speed $2\pi \cdot df \cdot t$. If the phase difference Φ_i increases as mentioned above, the above mentioned compensation means cannot compensate the error since the compensation operation of the compensation means is delayed as shown in FIG. 12. If the drift is negligible in comparison with the unit phase $\pi/4$, it is not necessary to compensate this drift. However, if the frequencies of the reference carrier wave and the input phase-modulated wave are incorrect, the drift must be compensated. A cascade arrangement comprising a subtractor S_2 , a code converter C_2 , an accumulator I_2 and a code converter C_3 is means for compensating this drift. The subtractor S_2 , the code converter C_2 and the accumulator I_2 forms compensating means similar to the cascade arrangement of the circuits S_1 , C_1 and I_2 mentioned above to compensate a drift component in the digits c_1^5 . In this case, however, the code converter C_2 produces complements for a range 256 different from the range of the code converter C_1 . In other words, since the output e_1^8 of the accumulator I_2 is formed by eight bits and the full range of this eight bits corresponds to the number 256, the output g_1^8 of the subtractor S_2 becomes a number "31 + 224 = 255" in a case where the output f_1^5 is equal to a number 31. The compensated output e_4^8 is applied to a code converter C_3 , in which the digits e_4^8 are converted to negative information so that the digits e_4^8 are subtracted from the digits b_4^{11} at an adder A_1 if the direction of the drift is negative. For this purpose, a number "224" is added to the digits e_4^8 at the converter C_2 similarly to the converter C_2 if the digits e_4^8 are included in a range from 16 to 31.

As mentioned above, the digits b_4^{11} obtained after normal compensation operation by the circuits S_1 , C_1 and I_1 and the digits h_1^8 obtained after drift-compensation operation by the circuits S_2 , C_2 , I_2 and C_3 are added to each other at the adder A_1 , so that phase-drift and phase-error caused by the reference carrier wave generated independently to the input phase-modulated wave can be detected completely without no delay by the use of compensation technique mentioned above. It is very difficult to perform digitally in a high precise manner this detection operation of phase-error by an automatic phase control circuit having a feed back loop if the number of digit is small.

The above-mentioned correcting digits i_1^8 obtained from the adder A_1 correctly indicates phase error. Accordingly, the phase error and phase drift included in the digits i_1^8 is eliminated by subtracting the correcting digits i_1^8 from the input digits a_1^8 at a subtracter S_3 .

However, noise included in the input phase-modulated wave causes slight jitter at each quantum phase position. Since the digits j_5^8 and the polarity combinations of three bits included in a signal element of the phase-modulated wave are shown in Table 4, the jitter caused by the noise is eliminated by adding digits R_1 to the digits j_5^8 at an adder A_2 so as to perform addition of a value $\pi/8$ and to produce digits l_2^4 shown in Table 4.

1	1	1	0			
1	1	1	1			

A delay circuit DEL is provided so that output digits m_3^1 indicate an immediately preceding signal element. Accordingly, when the digit m_3^1 is subtracted from digits l_2^4 at a subtracter S_4 , differential phase modulation component is eliminated, so that digits n_1^3 represent a fixed-reference phase-modulated signal.

Since the digits n_1^3 are pure binary codes while the phase-modulation of the input differential-phase modulated wave is performed by Gray code, the digits n_1^3 are converted to Gray code to obtain an correct output.

If a plurality of phase-modulated waves are applied to the input terminal A , the accumulators I_1 and I_2 and the delay circuit DEL must be added more circuits in proportion to the increase of the number of the phase-modulated waves in the code converter G .

The above mentioned example mentioned with reference to FIGS. 8, 10 and 11 can be also applied to demodulate a phase-modulated wave or waves having 2^n quantum phase positions for transmitting n -bits of binary information by each signal element as well as the phase-modulated wave of eight-quantum phase. Moreover, if a fixed-reference phase modulated wave or waves is/are to be demodulated, the delay circuit DEL and the subtracter S_4 may be eliminated so that the output of the adder A_2 is directly applied to the code converter C_4 .

What we claim is:

1. A phase detection system for at least one digital

60

phase-modulated wave, comprising:

an input terminal for receiving a digital phase-modulated wave;

5 a reference phase generator having means for generating a first reference carrier and a second reference carrier each having a frequency substantially equal to the frequency of said digital phase-modulated wave and having a phase difference 90° therebetween;

modulation product means coupled to the input terminal and the reference phase generator to produce a first modulation product of the first reference carrier and the digital phase-modulated wave and to produce a second modulation product of the second reference carrier and the digital phase-modulated wave;

conversion means coupled to the modulated product means to convert the first modulation product and the second modulation product to a converted signal indicative of a value corresponding to a phase difference between the digital phase-modulated wave and one of said first and second reference carriers; and

comparison means coupled to the conversion means to compare the converted signal with one of a plurality of possible discrete phase positions of the digital phase modulated wave so as to perform phase-detection of the digital phase-modulated wave.

30 2. A phase detection system according to claim 1, in which the conversion means comprises a pair of integrators each performing integration for each signal element of the digital phase-modulated wave.

3. A phase detection system according to claim 1, in which the conversion means comprises a pair of low pass filters.

4. A phase detection system according to claim 1, in which the system further comprises compensation means coupled to the comparison means to subtract a phase corresponding to a transmitted code and the reference phase from the phase position of the phase-modulated wave to obtain a phase error and having means to perform the phase compensation of the reference phase by the use of the phase error.

45 5. A phase detection system according to claim 1, in which the system further comprises a PCM coder arranged between the input terminal means and the modulation product means.

6. A phase detection system according to claim 5, in which the comparison means comprises phase-error detection means for detecting phase-error from lower digit values of the converted signal, a subtractor coupled to the conversion means and the phase-error detection means for subtracting the phase-error from all 55 digit values of the converted signal, and demodulation means coupled to the subtractor for performing demodulation of the phase modulated wave by the use of higher bits only of the output digital values of the subtractor.
